WAGON DRILL

George H. Fuehrer, Downey, Calif., assignor to Thor Power Tool Company, Aurora, Ill., a corporation of Delaware

Application January 11, 1954, Serial No. 403,339

3 Claims. (Cl. 255—51)

This invention relates to a wagon drill, and more particularly to means for raising and lowering the support for a pneumatic rock drilling apparatus.

Wagon drills, that is to say pneumatic rock drills mounted on wheeled frames or wagons, are frequently employed in mining, tunneling, and other drilling operations where it is desired that the drill have a rigid though readily moved support. Wagon drills conventionally embody a mast on which is mounted a drifter-type rock drilling apparatus. The drill steel of the drilling apparatus conventionally extends parallel to the mast and, when guided by a centralizer, is operable to form a relatively deep bore hole in the object being drilled.

It is highly desirable that the drilling apparatus be usable for both vertical and horizontal drilling, and also that it is adaptable for drilling at various angles and elevations. To this end the portion of the wagon or frame on which the mast is mounted should be capable of being raised or lowered to various elevations above the ground, and without lifting or lowering the wagon as a unit. Apparatus heretofore constructed for accomplishing such raising and lowering has embodied relatively complex screw means, fluid piston arrangements, and numerous other systems all of which have the disadvantages that they are complicated, relatively expensive, difficult to operate and subject to breakdown.

In view of the above factors characteristic of the field of wagon drills embodying means for raising or lowering the mast mounting, it is an object of the present invention to provide a wagon drill raising and lowering means which is extremely rugged and simple to operate, yet is operable to either raise or lower the drill to any desired elevation and maintain it at such elevation until a subsequent height adjustment is effected.

Another object of the invention is to provide a pair of ratchet elements independently operative to raise or lower the drill-supporting portion of a wagon drill rig, and locking means to hold the drill support at its elevated position despite the effects of extreme vibration such as occurs during drilling.

An additional object of the invention is to provide a wagon drill apparatus which may be adapted for drilling either horizontally or vertically, and at an infinite number of elevations and drilling angles.

These and other objects and advantages of the invention will appear upon reading the following specification and claims, and upon considering in connection therewith the attached drawings to which they relate.

In the drawings:

Figure 1 is a side elevational view of the lower portions of a wagon drill apparatus embodying the invention, showing the mast mounting member in its extreme upper position in solid lines, and in its extreme lower position in dashed lines;

2

Figure 3 is an enlarged fragmentary horizontal sectional view taken along line 3—3 of Figure 1;

Figure 4 is a vertical sectional view taken along line 4—4 of Figure 3;

Figure 5 is a transverse section on line 5—5 of Figure 4;

Figure 6 is a side elevational view of the pawl holding member and of the pawl which effects lowering of the drill rig, as viewed from the bottom in Figure 5 and with the ratchet rings and the end disc broken away to their midpoints; and

Figure 7 is a view corresponding to Figure 6 but showing the other side of the pawl holding member and the pawl which effects raising of the drill rig, as viewed from the top in Figure 5 and with the ratchet rings and end disc again broken away to their midpoints.

Referring to the drawings, and particularly to Figures 1 and 2, the wagon drill apparatus may be seen to comprise generally a front frame 10 and a tail frame 11 which are pivotally associated with each other at a pivot axis 12, and means 13 for pivoting the front and tail frames relative to each other to thus raise and lower pivot axis 12 between the solid and dashed line positions shown in Figure 1. During such raising and lowering, the mast portion 14 for the rig, and which is associated with the frames 10 and 11 at pivot axis 12, is shifted in a manner effecting a change in the height of drilling angle of the drill steel 15 of the apparatus.

The front frame 10, which is preferably formed of tubular components, comprises a horizontal cross member 17 the axis of which is coincident with the pivot axis 12, a pair of downwardly and laterally extending side struts 18 and 19, and a pair of front wheels 21 which are journaled on horizontal axially aligned stub shafts 22 at the lower strut ends. The upper ends of struts 18 and 19 are welded to the opposite end portions of cross member 17 and at points spaced inwardly from its ends, there being triangular brace plates 23 provided to form a rigid joint. Front wheels 21 are freely pivotable on stub shafts 22 except when locked against rotation by hand-operated brake members 24 of any suitable type.

Tail frame 11 comprises a pair of corresponding angularly related tubular members 26 and 27 which come together at an apex and are there associated with a tail wheel assembly 28. Wheel assembly 28 comprises a tail wheel 29, which is somewhat smaller than front wheels 21 but is of a similar rubber-tired construction, and means 30 to pivotally relate the tail wheel 29 with frame members 26 and 27. At their forward ends, remote from tail wheel 29, frame members 26 and 27 are pivotally associated with the extreme ends of horizontal cross member 17, but are adapted to be locked against pivoting relative to member 17, and thus front frame 10, by means next to be described.

Referring to Figure 3, the forward end of frame member 27 is shown as welded to a ring member 32 which in turn is rotatably mounted on the end of cross member 17, the inner and outer sides of the ring member being formed with frusto-conical surfaces 33 and 34, respectively. Inner frusto-conical surface 33 is adapted to seat against a corresponding surface 36 on a brake ring 37 welded around cross member 17. Similarly, outer frusto-conical surface 34 is adapted to seat against a corresponding surface 38 on an end cap 39 which is seated over the outer cross member end. End cap 39 is, in turn, associated with a bolt 40 which extends along pivot axis 12 for the full length of cross member 17, there being a nut 41 provided on the threaded bolt end 42 and seated against a washer 43 on the outer surface of end cap 39.

Figure 2 is a front elevational view of the solid line showing of Figure 1;

It is to be understood that the structure at the other end of horizontal cross member 17 is the same, except that the nut 41 is replaced by a conventional bolt head 44 as shown in Figure 2. With such a construction, tightening of nut 41 on bolt end 42 operates to force the end caps 39 inwardly against ring members 32, so that the frusto-conical surfaces 38 and 34 lock with each other as do the corresponding surfaces 33 and 36. The end caps 39 are keyed to cross member 17 by keys, not shown, so that a rigid braking action is created between surfaces 34 and 38, and surfaces 33 and 36, which effectively prevents pivoting of front frame 10 relative to tail frame 11. The frame components 10 and 11 being thus locked against pivoting relative to each other, vibration or other factors will not be operative to effect raising or lowering of pivot axis 12. Instead, the only method of pivoting the frame components 10 and 11 relative to each other, in order to change the pivot axis height, is to loosen the nut 41 and operate the means 13 to be described subsequently.

Referring again to Figures 1 and 2, the mast 14 is seen to comprise an I-sectioned beam only the lower portion of which is illustrated. This beam is associated with the cross member 17 by means of an adjustable saddle 46 which, in turn, is mounted on a sliding clamp 47 of any suitable type. By loosening bolts 48 on saddle 46, the mast 14 may be shifted transversely of cross member 17 to any desired axial position. Similarly, by loosening the clamp 47, the mast 14 and saddle 46 may be either pivoted about cross member 17 or shifted longitudinally of it. In this manner, the mast 14 may be pivoted to any angle and adjusted to a number of locations. This, when considered in conjunction with the means 13 for raising and lowering cross member 17 through pivoting of front frame 10 relative to tail frame 11, means that mast 14 may be shifted to substantially any position. It is to be understood that the mast 14 is associated with a suitable drifter motor and rock drilling apparatus, not shown. The rock drilling apparatus is, in turn, associated with the drill steel 15 which extends longitudinally of mast 14 and is guided by a centralizer indicated at 49.

Proceeding next to a description of the means 13 for pivoting front frame 10 relative to tail frame 11 and thus raising or lowering pivot axis 12 and mast 14, these means comprise a threaded shaft 51 pivotally associated with front frame 10 and tail frame 11, and a pair of pawl and ratchet assemblies 52 and 53 adapted to rotate shaft 51. To pivotally connect shaft 51 with front frame 10, a bracket 54 is welded at one end to strut 19 and is bifurcated at the other end to fit around the threaded forward portion of the shaft. Mounted between the bifurcations at the end of bracket 54 is an internally threaded cylindrical member 55 (Figure 3) having trunnions 56 (Figure 1) which rotate in corresponding trunnion apertures in the bracket. With such a construction, the shaft 51, which is threadedly associated with cylindrical member 55, may pivot relative to strut 19 and between the solid and dashed line positions indicated in Figure 1.

To pivotally associate shaft 51 with tail frame 11, a bearing sleeve 58 is formed integral with and transverse to the end of a stub shaft 59, the latter being journaled in a bearing 61 which is welded to the underside of tail frame component 27. Sleeve 58 fits around an unthreaded upper or rear portion of shaft 51, and as illustrated best in Figure 4. Longitudinal shifting of shaft 51 relative to bearing sleeve 58 is prevented by a lower bearing ring 62, held in position by a pin 64 extended therethrough and through shaft 51, and by a thrust ball bearing 63. The ball bearing 63 is seated between the upper end surface of bearing sleeve 58 and a flange 65 on the enlarged cylindrical end portion 66 of the shaft.

According to the invention, the pawl and ratchet assemblies 52 and 53 comprise, respectively, internally toothed ratchet rings 68 and 69, and cooperating pawls 71 and 72 mounted on shaft end portion 66. It is emphasized

that only one pawl need be provided for each ratchet ring, and that the relative arrangements between the pawls and ratchet rings are such that the assemblies 52 and 53 operate in opposite directions. Thus, the mounting of pawl 71 relative to ratchet ring 68 is such that clockwise rotation of the ratchet ring, as viewed in Figure 5, will effect clockwise rotation of shaft 51, while counterclockwise rotation of ring 68 will effect merely its free-wheeling or shifting relative to the pawl. On the other hand, clockwise rotation of ratchet ring 69 will effect free-wheeling or shifting, the arrangement of the pawl 72 being such that it locks with ratchet ring 69 only when the latter is moved counterclockwise.

In the more specific construction of the pawl and ratchet elements, the lower assembly 53 comprises the ratchet ring 69 which is formed with an annular recess at its lower edge to seat over flange 65, the unrecessed upper portion of the ratchet ring being provided with teeth 73 which extend inwardly to adjacent the cylindrical shaft end 66. To accommodate the pawl 72 of lower assembly 53, a cut or recess 74 is formed for the full length of shaft end 66 and for part of its flange 65, as best shown in Figures 5 and 6, the cut having one wall formed on a radius of cylinder 66 and the other wall formed on a chord thereof. At the junction of the radial and chordal walls is formed a longitudinal bore 76 which communicates with cut 74 and is adapted to receive the cylindrical pawl body 77. The pawl body 77 is integral with a flat lug portion 78 which extends outwardly into engagement with ratchet teeth 73. Bias means 79 are provided to urge lug 78 into engagement with the ratchet teeth, and preferably comprise a spring-pressed cup 80 seated in transverse aperture in cylinder 66 as illustrated in connection with upper assembly 52 in Figure 5.

The upper pawl and ratchet assembly 52 comprises ratchet ring 68 the upper and inner portion of which is provided with an annular recess to receive an end disc 82, the latter being mounted around a threaded reduced end portion 83 formed axially on cylinder 66. The remaining or lower portion of the inner ratchet ring wall is formed with teeth 84 which are engaged by a lug portion 85 of pawl 71. Lug portion 85 is integral with a cylindrical pawl body 86 which is inserted in a longitudinal bore 88 in cylindrical shaft portion 66. As in the case of bore 76 for pawl 72, the bore 88 communicates with a cut or recess 89, shown in Figures 5 and 7, also having chordal and radial side walls. Recess 89 is, however, of substantially lesser depth than recess 74. Bias means 90, comprising the spring-pressed plunger 80 as in the case of bias means 79 for pawl 72, are provided as shown in Figure 5 to urge pawl lug 85 into engagement with teeth 84.

It is to be noted upon reference to Figure 5 that the pawls 71 and 72 and associated bias means 90 and 79 are spaced from and symmetrical to a plane which contains the axis of shaft 51 and its enlarged end portion 66. Thus, both lugs 85 and 78 extend in generally the same direction from the cylindrical pawl bodies 86 and 77, and act against opposite sides of the ratchet teeth 84 and 73. It follows that pawl 71 locks with ratchet ring 68 when the latter is operated in one direction, while pawl 72 locks with ratchet ring 69 when it is operated in the opposite direction. In either instance, ratchet ring rotation is effected by placing the end of a wrench, not shown, in a bore 93 formed in a lug 94 on each ratchet ring.

In assembling the assemblies 52 and 53 with cylindrical shaft portion 66, the bias means 90 and 79 are first mounted in position, after which the ratchet rings 68 and 69 are fitted over cylinder 66, with ring 69 seated on flange 65 as shown in Figures 4, 6 and 7. The pawl 72 is then inserted downwardly through bore 76 and recess 74, after which a spacer pin 95 is inserted in the bore 76 above the cylindrical pawl body 77. Similarly, the pawl 71 is inserted in bore 88 and recess 89, although no spacer pin is necessary due to the elevated position of the pawl

The end disc 82 is then mounted over threaded end portion 83, and a nut 96 is threaded thereover to hold the assemblies in position. It is to be noted that the end disc 82 seats against pawl 71 and against the spacer pin 95, so that both pawls are maintained in the desired longitudinal positions. To insure against disassembly of the structure due to the extreme vibration caused by operation of the drill, a cotter pin 97 is inserted through nut 96 and shaft end 83, and a key pin 99 (Figures 5 and 6) is mounted in corresponding bores in end disc 82 and cylinder 66, the mounting of the key pin being effected prior to positioning of the end disc and nut.

In the operation of the wagon drill apparatus, the brakes 24 on front wheels 21 are loosened, and the entire apparatus is pulled or pushed to the desired location, for example by means of a draw bar 100 shown in Figure 1 as connected to tail wheel assembly 28. Thereafter, the brakes 24 are turned to lock the front wheels 21, and the saddle 46 and clamp 47 are adjusted until the mast 14 and associated drill steel 15 are in the desired positions. Simultaneously with the adjustment of mast 14, or either before or after the adjustment if desired, the nut 41 (Figure 3) is turned to permit end caps 39 to shift away from ring member 32, so that the cooperating frusto-conical surfaces 34 and 38, and 33 and 36, come out of locking engagement and permit pivoting of front frame 10 relative to tail frame 11. One or the other of the ratchet assemblies 52 or 53 is then operated to effect either raising or lowering of pivot axis 12, and thus mast 14, as may be required.

For example, if the rig is initially in the pivoted position illustrated in solid lines in Figure 1, and it is desired to lower the rig to the dashed line position, a wrench end is placed in the bore 93 of ratchet ring 69 of lower ratchet assembly 53, and the wrench is pumped back and forth in the manner of a ratchet wrench. During each counterclockwise stroke of the ratchet ring 69, as viewed from the upper end of the raising and lowering means 13, the shaft 51 will turn counterclockwise with the ratchet ring. This will effect, due to the construction of the threads on shaft 51, a raising of shaft 51 in cylindrical threaded member 55 (Figure 3) to increase the angle between the front and tail frames. During each clockwise stroke of the ratchet ring 69, the lug portion 78 of pawl 72 merely compresses bias means 79 to permit free-wheeling or shifting of the ratchet ring relative to the shaft, so that no shaft rotation results. As this operation is continued, the angle between front frame 10 and tail frame 11 increases until they are past dead center as illustrated in dashed lines in Figure 1, the mast 14 and drill steel 15 having then been shifted to a generally horizontal position as illustrated. This horizontal mast position is much lower than the mast position which would result if clamp 47 were loosened, and the mast pivoted about cross bar 17, when the latter is in its upper or solid line position.

The operation may be reversed by merely removing the wrench from bore 93 of lower ratchet ring 69, and inserting it in the corresponding bore of upper ratchet ring 68. Since, as previously stated, the upper ratchet assembly acts oppositely to the lower, a pumping of the upper ratchet ring will effect rotation of shaft 51 in the opposite direction to decrease the angle between front frame 10 and tail frame 11, and until these elements are in the initial or solid line positions shown in Figure 1. After the desired position is reached, the lock nut 41 is turned to prevent further rotation of the frame elements relative to each other, to thus hold the drill in the desired elevation regardless of extreme vibrational stresses.

It is pointed out that the bracket 54 is of a length sufficient to space the lower pivot point for shaft 51 a substantial distance rearwardly from the plane of front frame 10. This, together with the fact that the upper pivot point for shaft 51 is spaced adjacent the plane of tail frame 11 and a substantial distance from pivot axis 12, means that a

large amount of pivoting may be effected with a relatively short shaft. Also, and very importantly, the frames may be pivoted past their aligned or dead center positions, and as shown in dashed lines in Figure 1.

5 While the particular apparatus herein shown and described in detail is fully capable of attaining the objects and providing the advantages hereinbefore stated, it is to be understood that it is merely illustrative of the presently preferred embodiments of the invention and that no limitations are intended to the details of construction or design herein shown other than as defined in the appended claims.

I claim:

1. A wagon drill apparatus, comprising a front frame having a horizontal cross bar and a pair of wheeled struts, a tail frame comprising a pair of angularly related components connected at their apex to a tail wheel, means to pivotally connect the ends of said tail frame components remote from said tail wheel to opposite end portions of said cross bar, a mast adjustably mounted on said cross bar and adapted to support a pneumatic rock drill, an internally threaded member pivotally mounted on one of said struts, a bearing pivotally mounted on the corresponding one of said tail frame components, a shaft journaled in said bearing and threaded through said internally threaded member, means to prevent longitudinal movement of said shaft relative to said bearing, a first pawl mounted on said shaft on the opposite side of said bearing from said internally threaded member, a first internally toothed ratchet ring mounted on said shaft outwardly of said first pawl, said first pawl and first ratchet ring being so constructed and arranged that turning of said first ratchet ring in a first direction will cause said first pawl and first ratchet ring to lock with each other and effect turning of said shaft in said first direction, and turning of said first ratchet ring in a second and reverse direction will cause said first pawl and first ratchet ring to shift relative to each other, a second pawl mounted on said shaft adjacent said first pawl, and a second internally toothed ratchet ring mounted on said shaft outwardly of said second pawl, said second pawl and second ratchet ring being so constructed and arranged that turning of said second ratchet ring in said second direction will cause said second pawl and second ratchet ring to lock with each other and effect turning of said shaft in said second direction, and turning of said second ratchet ring in said first direction will cause said second pawl and second ratchet ring to shift relative to each other.

2. The invention as claimed in claim 1, in which said means to connect said tail frame components and cross bar comprises a pair of mounting rings mounted around said cross bar and each having frusto-conical end surfaces, and in which a brake ring is welded on said cross bar inwardly adjacent each mounting ring and is formed with a frusto-conical surface corresponding to the adjacent mounting ring surface, an end cap is mounted over said cross bar outwardly adjacent each mounting ring and is formed with a frusto-conical surface corresponding to the adjacent mounting ring surface, and a shaft is mounted axially in said cross bar and adapted upon tightening of a nut thereon to draw said frusto-conical surfaces together and lock said front frame against pivoting relative to said tail frame.

3. Apparatus for effecting relative pivotal movement between two pivotally connected frames of a wagon drill rig, which comprises a threaded member pivotally mounted on one of said frames, a bearing sleeve pivotally mounted on the other of said frames, a shaft threadedly associated with said threaded member and journaled in said bearing sleeve, means to prevent axial shifting of said shaft relative to said bearing sleeve, a first pawl mounted on said shaft, first internally toothed ratchet ring mounted on said shaft outwardly of said first pawl, said first pawl and first ratchet ring being so constructed and arranged that turning of said first ratchet ring in a first direction

will cause said first pawl and first ratchet ring to lock with each other and effect turning of said shaft in said first direction, and turning of said first ratchet ring in a second and reverse direction will cause said first pawl and first ratchet ring to shift relative to each other, a second pawl mounted on said shaft, and a second internally toothed ratchet ring mounted on said shaft outwardly of said second pawl, said second pawl and second ratchet ring being so constructed and arranged that turning of said second ratchet ring in said second direction will cause said second pawl and second ratchet ring to lock with each other and effect turning of said shaft in said second direction, and turning of said second ratchet

ring in said first direction will cause said second pawl and second ratchet ring to shift relative to each other.
